UNITED STATES PATENT OFFICE.

FREDERICK B. WAIBEL, OF NEWARK, NEW JERSEY.

DIP-TANK WITH AUTOMATIC COVER.

1,020,526.

Specification of Letters Patent. Patented Mar. 19, 1912.

Application filed October 18, 1911. Serial No. 655,446.

To all whom it may concern:

Be it known that I, FREDERICK B. WAIBEL, a citizen of the United States, residing in the city of Newark, in the county of Essex 5 and State of New Jersey, have invented certain new and useful Improvements in Dip-Tanks with Automatic Covers, of which the following is a full, clear, and exact description, such as will enable others skilled in the art to which it pertains to make, construct, and use the same, reference being had to the accompanying drawings, and to letters of reference marked thereon, forming a part of this specification.

15 The present invention relates to an improved automatic apparatus by which fires in, or which threaten the dip tank so extensively employed in factories, may be prevented from spreading, or completely extinguished, thereby saving the contents of 20 the tank and preventing dangerous explosions.

The object of this invention is to provide 25 a suitable stand, preferably made from angle-iron, which supports the tank containing the varnishes, lacquers, and the like, said stand being provided with a cover held in open or locked position by holding means 30 which are secured to the sides of said stand, said means being connected in any well-known manner, preferably by a cable or wire provided with a series of fusible links which when the temperature of the room is 35 abnormally increased, melts, thereby permitting the holding means secured to the sides of the stand which hold the covers in open or locked position to operate and release said covers, thereby closing the tank 40 and preventing the access of air or fire thereto.

A preferred construction of a dip tank with automatic covers embodying my invention is shown in the accompanying drawings, in which—

Figure 1 represents a side elevation of a dip tank embodying my invention. Fig. 2 represents a plan view of the same. Fig. 3 represents an end elevation of the same, 50 the spring-actuated covers being shown closed, but the cover holding means being shown in operative position holding the covers shown in dotted lines in open and locked position. Fig. 4 represents a similar view 55 showing the holding means in their inoperative position after the covers have been

released. Fig. 5 represents an enlarged view of one of the cover holding levers; and Fig. 6 represents a similar view of a modified form of a cover holding lever.

Similar letters of reference refer to like parts throughout the specification and drawings.

The tank *a* shown in the drawings is of the ordinary type, commonly used in factories and known as a dip tank, supported on a suitable stand *b*, preferably made from angle iron. The covers *c*, *c* are of ordinary construction, preferably made from sheet metal, hinged at *d*, *d*, so as to cover the entire top of the tank *a* when closed.

60 The automatic closing of the covers *c*, *c* may be effected by any suitable means, such as spiral springs *e*, *e* tending constantly to close the covers.

65 The covers *c*, *c* are held open against this tendency of the springs by the catches *s*, *s*, pivotally attached to the outer ends of the levers *f*, *f*, said levers being pivotally attached to the end frames *g*, *g* of the supporting stand at *h*, *h*. These catches *s*, *s* are maintained in a downward position to hold the covers open by means of a flat spring *i*, one end of which is secured in a slot *i'* in the lever *f* and the other end of which bears 70 against the upper and outer portion of the catch *s* close to that point where the catch is provided with a receiving or cut-out portion *j*, which engages with the end of the cover *k*.

75 Two sets of cover holding means are employed to hold the covers in open and locked position, one set on each end of the tank supporting stand. These cover-holding means consist of the levers *f*, *f*, which as previously 80 stated, are pivotally attached to the end frames *g* of the tank stand. The inner ends of the levers *f* are connected by means of a stud *l* secured to one lever which passes through a slot *m* formed in the other lever. 85 These levers or cover-holding means are held in their operative position as shown in Fig. 3 of the drawings, by a chain *n*, the ends of which are fastened to the apertured ears *n'* of the levers and which then passes 90 over the pulleys *o* which are conveniently mounted in uprights *p* of the stand *b*.

95 The automatic releasing of the cover holding means or levers may be effected by any suitable means, such as a spiral spring *q*, 100 tending constantly to pull the cover-closing means down as shown in Fig. 4 of the draw-

ings, one end of the spiral spring *q* being fastened to the stud *l* of the lever *f*, the other being fastened in any convenient manner to the cross-piece *g* of the stand *b*.

- 5 In order to render the operation of the cover-releasing means as sensitive and prompt as possible, the chain *n* is provided with a series of fusible links *r* of any commercial form, which while sufficiently strong 10 at ordinary temperatures to perform their function, will, when the temperature is abnormally increased, as in the case of fire, melt, thereby causing the levers secured to the sides of the stand which hold the covers 15 in open or locked position to operate and release said covers, thereby entirely closing the tank and preventing access of air or fire thereto.

In Fig. 6 of the drawings, I have shown 20 a simple form of a lever *t*, forming one of the levers which constitute the cover-holding means, in which I have dispensed with the catch *s* and spring *i*. This lever *t* is pivotally attached to the end frames *g* in substantially the same manner as the lever *f*, and is 25 also provided with a receiving or cut-out portion *u*, designed to engage with the end of the cover *k*. The lever shown in the drawings is also provided with a stud *l*, designed to pass through a slot formed in the other lever.

Experience has demonstrated that the organization above described is a highly efficient one, and while the device described is 35 the preferred embodiment of my present invention, I do not care to restrict myself to the exact details of construction, combination, and arrangement herein set forth, it being obvious that minor variations thereof 40 not involving the exercise of invention may be made by any skilled mechanic, and such departures from what is herein described and claimed not involving invention, I consider as within the scope and terms of my 45 claims.

I claim:

1. An apparatus of the class described, comprising a supporting stand for the tank, spring-actuated covers secured to said stand,

holding means secured to the stand for holding said covers in open and locked position, means for releasing said holding means interposed between the stand and said holding means and a fusible connection between said holding means rendered inoperative by heat 55 to release the cover and close the tank.

2. An apparatus of the class described, comprising a supporting stand for the tank, spring-actuated covers secured to the stand, a pair of levers secured to the ends of the stand pivotally connected and provided with means for holding said covers in open and locked position, uprights fastened to the end of the stand in which are secured pulleys, and a chain provided with fusible links 60 passing over said pulleys, the ends of said chain being secured to said levers, the fusible links being rendered inoperative by heat 65 to release the covers and close the tanks.

3. An apparatus of the class described, comprising a supporting stand for the tank, spring-actuated covers secured to the sides of the stand, holding means secured to the ends of the stand provided with pivotally arranged spring-pressed catches for holding 70 said covers in open and locked position, a spring secured to the stand and to said holding means and a fusible connection between said holding means rendered inoperative by heat 75 to release the cover and close the tank. 80

4. An apparatus of the class described, comprising a supporting stand for the tank, spring-actuated covers secured to said stand, holding means secured to the stand for holding said covers in open and locked position, 85 a spring, one end of which is secured to said holding means and the other end of which is secured to the stand and a fusible connection between said holding means rendered inoperative by heat to release the 90 cover and close the tank.

This specification signed and witnessed this 9th day of October, 1911.

FREDERICK B. WAIBEL.
